UNITED STATES PATENT OFFICE.

JOHN B. MITCHELL, OF IPSWICH, MASSACHUSETTS.

HALTER.

SPECIFICATION forming part of Letters Patent No. 415,546, dated November 19, 1889.

Application filed April 11, 1889. Serial No. 306,826. (No model.)

To all whom it may concern:

Be it known that I, JOHN B. MITCHELL, a citizen of the United States, residing at Ipswich, in the county of Essex and State of Massachusetts, have invented a new and useful Halter, of which the following is a specification.

This invention relates to cattle-hitching devices of that class intended for use in stables, barns, and the like; and it consists in the construction and novel combination and arrangement of parts hereinafter fully described, illustrated in the accompanying drawings, and pointed out in the claims hereto appended.

In the accompanying drawings, which form a part of this specification, Figure 1 is a perspective view of my improved halter complete. Fig. 2 is an enlarged central longitudinal section of the hook and staple. Fig. 3 is an enlarged plan view of the plate and the knot for tying the rope halter therein. Fig. 4 is a detail view of the staple.

The same letters of reference are applied to corresponding parts in the several views of the drawings.

The letter S designates a staple driven, bolted, or screwed into a beam B of the stall. At the center of its front end it is cut away or recessed on its upper face, as at s, for a purpose to be hereinafter specified.

H is a hook having a point, as h, and bent over nearly against the body, leaving a space h' therebetween only a trifle larger than the thickness of the staple at the point where the cut-away portion s is located.

G is a chain connected to an eye in the opposite end of the hook and leading to a similar eye in the inner end of a bar R, the latter having a squared body r, a rounded portion r', and head r² at its outer end.

C is a cord, rope, or other halter knotted at k at one end, passed through an eye I in a plate P looped in its body, and at its other end passed again through another eye I in said plate. The plate P is swiveled upon the rounded shank r' of the bar R, the free end of the halter-rope C tied in any suitable manner into the eye therein, through which it is passed, and the whole device is ready for use.

I prefer to use the form of knot shown in Fig. 3 for tying the rope into the plate P.

This knot is especially adapted for use in this connection, and repeated experiment and long-continued usage have led me to believe it is the best knot that can be used, as it is quickly tied or untied or adjusted, and does not wear the rope either upon itself or upon the corners of the eyes in the plate P, yet at the same time is a firm and unyielding knot. The rope C is first passed inwardly at c, through one of the eyes I, (of which there are two at this side of the swivel,) then bent over and passed outwardly through the other eye, as at c', then bent around the edge of the plate at c², and passed laterally across the inner face of said plate beneath the loop of the rope between the two holes I I, all as plainly illustrated in the drawings, and as will be clearly obvious to a person skilled in the art.

My improved halter having been constructed as above described, and a staple S driven at about thirty inches height from the ground into some conveniently-located beam in the stall wherein it is desired to fasten the animal, the rope C is first knotted at one end, as at k, and its body passed through the single eye I in the plate P. It is then passed around the neck of the animal, its free end passed inwardly, preferably through the outer of the two eyes I, near the other end of the plate P, passed outwardly through the remaining eye, bent laterally over the edge of the plate, and its free end passed under the loop at the back of said plate. The rope is then drawn up to the desired degree of tightness around the animal's neck, and all slack taken up, as will be readily understood. The chain G is then grasped in the hand of the attendant, and the animal can be led to water or elsewhere. When it is desired to fasten him in his stall he is led thereinto, the hook H passed upwardly behind and into the staple S, and then brought forward, so that the space h' passes over the reduced portion s of the staple. The body of the hook is then released, and its weight, which is comparatively considerable, together with that of the chain G, turns it downwardly around the staple S, so that the space h' no longer stands in alignment with the reduced portion s, and all liability of accidental and automatic disengagement is avoided.

The animal can lie, stand, eat, drink, and

avail himself of the considerable freedom allowed by the length of the chain, all without the halter becoming detached either from his neck or from the staple S, and the swivel 5 in the plate P prevents all liability of twisting, so common and so disagreeable in farm and stable devices of this character.

Having thus described my invention, I claim—

- 10 1. The staple S, reduced in thickness at one point at s , in combination with the hook H, having a turned-over point h , leaving a space h' between said point and the shank of the hook, said space being just sufficient to admit the reduced portion of said staple, the body of said hook being extended horizontally beyond said point to give it weight, all as and for the purpose set forth.
- 15 2. The chain G and the bar R, connected thereto, said bar comprising a squared body r , a rounded portion r' , and a head r^2 , in combination with a plate P, centrally swiveled upon said rounded portion of the bar between its body and head, and a rope halter having 20 its ends connected to the opposite ends of said plate, substantially as hereinbefore set forth.
- 25 3. The plate P, having a single eye I near one end and a pair of adjacent eyes II near its

other end, in combination with the rope C, tied into said single eye at one end, its other end being detachably and adjustably tied into said pair of eyes, and with a chain G, connected to said plate, the whole constructed and adapted for use substantially as herein described. 30

35 4. The staple S, reduced in thickness at one point, as at s , in combination with the improved halter herein described, said halter comprising a hook H, whose point is open on the upper side of its body to a distance only 40 equal to the thickness of the staple at its reduced point, a chain connected to the inner end of said hook, a bar R, connected to the other end of said chain, a plate P, centrally swiveled upon the outer end of said bar, and 45 a rope C, tied to one end of said plate and detachably connected to the other end thereof by an adjustable knot, substantially as herein specified.

50 In testimony that I claim the foregoing as my own I have hereto affixed my signature in presence of two witnesses.

JOHN B. MITCHELL.
